(57) **CLAIM**

The ornamental design for a portable food buffet cooler, as shown and described.

DESCRIPTION

FIG. 1 is a perspective view from above of my new design for a portable food buffet cooler.

FIG. 2 is an elevational view or the front of the cooler shown in FIG. 1.

FIG. 3 is a top plan view of the cooler shown in FIG. 1.

FIG. 4 is a bottom plan view of the cooler shown in FIG. 1.

FIG. 5 is an end elevational view of the cooler shown in FIG. 1.

The opposite end view would be a mirror image thereof.

FIG. 6 is an elevational view of the back of the cooler shown in FIG. 1.

FIG. 7 is a cross sectional view through line 7-7 of FIG. 3; and,

FIG. 8 is a cross sectional view through line 8-8 of FIG. 3.
